[57] CLAIM

The ornamental design for a reconfigurable toy construction vehicle, substantially as shown and described.

DESCRIPTION

FIG. 1 is a side perspective view of a reconfigurable toy construction vehicle showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof, the side opposite being a mirror image;

FIG. 7 is another side perspective view of the design shown in FIGS. 1 through 6 in a humanoid robot reconfiguration;

FIG. 8 is a front elevational view thereof;

FIG. 9 is a rear elevational view thereof;

FIG. 10 is a top plan view thereof;

FIG. 11 is a bottom plan view thereof; and,

FIG. 12 is a side elevational view thereof, the side opposite being a mirror image.
